UNITED STATES PATENT OFFICE

93,623

DESIGN FOR AN OPTICAL REPRODUCING DEVICE

Morris Kaplowitz, Brooklyn, N. Y., assignor to
Microphone Corporation of America, Brooklyn,
N. Y.

Application June 14, 1934, Serial No. 52,174

Term of patent 14 years

To all whom it may concern:

Be it known that I, MORRIS KAPLOWITZ, a citizen of the United States, residing at Brooklyn, in the county of Kings and State of New York, have invented a new, original, and ornamental Design for an Optical Reproducing Device, of which the following is a specification, reference being had to the accompanying drawing, forming a part thereof.

The figure is a perspective view of my optical reproducing device.

I claim:

The ornamental design for an optical reproducing device as shown.

MORRIS KAPLOWITZ.
